CLAIM

The ornamental design for a pedal for a bicycle, as shown.

DESCRIPTION

FIG. 1 is a perspective view of a pedal for a bicycle showing my new design taken from the top, front and right side;

FIG. 2 is a perspective view thereof taken from the top, rear and left side;

FIG. 3 is a top plan view thereof, it being understood that the bottom is a mirror image of the top as shown herein;

FIG. 4 is a right side elevation view thereof; and

FIG. 5 is a left side elevation view thereof.

FIG.1

FIG.2

FIG.3

FIG.4
